GAME APPARATUS FOR PRACTICE USE
BY LAWN BOWLERSDenison W. Grant, 1 Crescentview Drive, Grantland
Park, Franklin, Pa.
Filed Feb. 29, 1960, Ser. No. 11,671
5 Claims. (Cl. 273—39)

This invention relates to game apparatus, specifically to apparatus cooperative with the bowl and jack used in the game of lawn bowling and available for use in a restricted space, for example in a living room, which will yield results comparable, from an index standpoint, to the results obtained in the actual game of lawn bowling, the apparatus being therefore valuable for practice in playing the game of lawn bowling in restricted areas and enabling the bowler to improve his game.

In lawn bowling the greens are bounded by shallow ditches and may be of various lengths and widths. A length of 120 feet and a width of 15 feet may be assumed as a fair example. The bowling balls, known as "bowls," are spheroidal and are rolled in the plane of their greater diameter (approximately 5 inches), in the direction of their plane of less diameter (approximately 4 $\frac{1}{8}$ inches) being weighted on one side. The target is a small white ball of 2 $\frac{1}{2}$ inches in diameter known as the "jack." According to the rules of the game, the jack is initially positioned by rolling or placement and its distance from the remote ditch (in the direction in which the bowl is thrown) is not less than six feet. The bowler stands upon a mat which may be placed in different positions, according to the rules of the game, and in throwing the bowl, must keep one foot on the mat. The object of the game is to have the bowl when it comes to rest as close to the jack as may be possible within the bowler's skill. The rules of the game provide for flexibility in respect to the length of the green (using the word "length" to signify the direction in which the bowl is thrown), the position of the jack and the position of the mat. The bowl, losing momentum as it rolls and being heavier on one side, toward the end of its roll will travel in a curved path known as its "bias." In throwing the bowl, if its heavier side be at the right the bias will be toward the right and if its heavier side be at the left the bias will be toward the left.

The principal object of the invention is to provide apparatus for use in a restricted space, for example (and of course without limitation) in a living room having a dimension of 25 feet in one direction, in which the carpet (or other supporting surface) is utilized as the "green" and the instruments of play are the actual bowls and jack, the players throwing the bowl with the force which they usually exercise in actual play and having the assurance that the results of the approach of the bowl to the jack, despite the small space available, will be fairly comparable to the results which they would have attained in the actual play of the game. Thereby, and by dint of repeated practice throws of the bowl, their actual play of the game will be improved.

Further objects are to provide apparatus which will be stable in use, light in weight and readily portable, small in compass and convenient for storage, and which will have appropriate safeguards against the effects of "wild" throws such as are occasional in the actual play of the game.

Apparatus in accordance with the invention embodies a combination of elements including a resilient rebound cushion composed of suitable yieldable and resilient material, foam rubber being ideal, the cushion being of trapezoidal cross section with a length of the order of a yard, a vertical dimension substantially greater than the maximum diameter of the bowl, and an inclined active face

2

in such overhanging relation to the surface along which the bowl is thrown that the bowl cannot bounce upon its return or recoil movement and a rigid frame within which the cushion is fitted and by which it is securely held, the frame to be placed against any suitable back-stop such as the wall of a room or, if the game be played outdoors, two or more stakes anchored in the ground, the frame preferably carrying a pair of hinged wings, one located at each end and which are foldable to positions adjacent the inclined face of the cushion when the apparatus is not in use and are movable into forwardly projecting and divergent relation which they occupy during the use of the apparatus, the wings providing protection against wild throws. The jack is located at a suitable distance in front of the cushion, for example five or six feet and may be rolled to, or placed in, its position, and the bowls are thrown against the cushion. The cushion has both a yielding quality and a resilient quality. By virtue of its yielding quality the cushion checks the momentum of the bowls as thrown with full force and by virtue of its resilient quality and the fact that the bowls are heavier at one side it causes the rebound of the bowls in a direction at an angle to their path as thrown by the bowler. In their rebound travel the bowls move comparatively slowly and after a short straight length of their rebound travel their curved bias commences. The player effects his full delivery of the bowl, the same as on the actual bowling green, and after a period of practice will get results which are reasonably comparable with the results of his similar delivery of the bowl on the bowling green, the skill of the player being exercised to cause the bowl to come to rest as close as possible to the jack whatever its position may be in its remoteness from the cushion.

More than one player may simultaneously use the apparatus for the essential purpose of practice. However, as the players continue their practice use of the apparatus, they may also utilize the apparatus as a game according to rules upon which they may agree and with scoring similar to the scoring in the actual game of lawn bowling.

40 In the drawings:

FIGURE 1 is a perspective view of the apparatus and also shows the jack and the bowl thrown by a player and in a position at rest near the jack.

FIGURE 2 is a plan view of the apparatus, the wings being shown in the parts broken away by reason of the space limitation of the drawing.

FIGURE 3 is a vertical sectional view on the line 3—3 of FIGURE 2.

FIGURE 4 is a horizontal sectional view on the line 4—4 of FIGURE 3 with frame parts shown in plan and with the wings shown in dot and dash lines in their folded relation.

FIGURE 1 shows the apparatus of the invention in association with the jack J and the bowl B which is assumed by rebound to have reached a position as close to the jack as the player has been able to effect.

The cushion 1 is composed of a solid section of suitably yieldable and resilient rubber, foam rubber being ideal for the purposes in view. The cushion has a length of three or four feet and its functional dimensions are, of course, subject to variation within practical limits, the recommended dimensions being a height of eight inches, a width across the top of seven inches and a width across the bottom of four inches, the cushion thereby having a body amply sufficient to withstand the impact of the bowl and upon such impact to react against the bowl and having an active front face 2 which extends well above the bowl and is in a suitably inclined plane whereby it overhangs the floor F (or other supporting surface) along which the bowl B is thrown, the face 2 meeting the bottom face at an obtuse angle and meeting the top at an acute angle, and its lower edge being indicated in

FIGURES 2 and 4 by the broken line X. While the inclination and extent of the face 2 may be varied within practical limits it is always such that, as overhanging the floor F and the bowl B, it will overcome any tendency of the bowl B to bounce during its return or recoil travel.

The cushion 1 is securely held in and by a supporting frame 3 which may be composed of wood and which includes a rear bar 4 adjoining the vertical rear face of the cushion 1, forwardly projecting side bars 5 secured to the bar 4 at its ends and which adjoin the vertical end faces of the cushion 1, the side bars projecting forward to some extent beyond the active face 2 of the cushion and cushion securing members 6 attached to the inner faces of the projecting portions of the bars 5 and having inclined cushion engaging faces 7 which uniformly bear with some degree of clamping pressure upon the ends of the inclined face 2.

The apparatus preferably includes wings 8 and 9 connected by piano type hinges 10 to the respective side bars 5. In the use of the apparatus the wings project in diverging relation forwardly from the bars 5, their function being to intercept any wild throws. The cushion securing members 6 have outer edge faces parallel to and terminating short of the outer edge faces of the side bars 5 and thereby provide rabbets 11 and 12, the rabbet 11 at the right (FIGURE 1 being considered) being of suitably greater depth than the rabbet 12 at the opposite side of the frame. The rabbets 11 and 12 enable the folding of the wings 8 and 9 in overlying relation when the apparatus is to be stored in a closet. By reason of the greater depth of the rabbet 11 the wing 8, as sufficiently indicated in FIGURE 4, may be folded into a position in which it is adjacent the active face 2 of the cushion and the wing 9 may thereafter be folded into a position in which it overlies the wing 8, the wings as folded being in substantially parallel relation with the wing 9 parallel to the rear bar 4 of the frame 3.

The jack J may be positioned at the right or left of the center line. The bowl B may be thrown perpendicularly or at an angle to the face 2. With the bowl B thrown perpendicularly its rebound movement will be at an angle to the right or left of the perpendicular line, accordingly as the heavier side of the bowl may be at the right or left, the angle of such recoil or return movement of the bowl being of maximum degree to the perpendicular line. If the bowl be thrown along a line at an angle to the face 2 its recoil or return path will, of course, be at a less angle to the perpendicular, the particular degree of angularity depending upon the angle of its travel as thrown. In general, the greater the angle to the perpendicular line of the bowl B as thrown, the less will be the angle to the perpendicular line of the bowl B in its return movement. These characteristics, among others, challenge the player's skill and the player, by dint of repeated practice efforts, will improve his control of the bowl and will thereby have correspondingly improved control in the actual playing of the game of lawn bowling.

When the bowl B as thrown strikes the face 2 it will depress the rubber of the cushion to some extent as sufficiently indicated by the broken line position Y in FIGURE 3 and a substantial percentage of its momentum will be absorbed by the cushion 1. The cushion being resilient will, of course, return to its normal outline and at the same time will impel the bowl on its angular return path, the bowl ultimately coming to rest in a position adjacent the jack and as close to the jack as may be in accord with the bowler's skill.

It will be apparent from the foregoing description that the apparatus of the invention is light in weight, compact in structure and readily portable from its place of storage to its place of use, either indoors or outdoors.

I claim:

1. A portable game apparatus for practice use by lawn bowlers in connection with a standard lawn bowl, having one side heavier than the other and a standard jack, comprising, in combination: a resilient rebound cushion composed of a solid section of yieldable and resilient material having a length of the order of three feet for support upon a floor, having a body of uniform cross sectional shape and ample dimensions to withstand and cushion the impact of the bowl as thrown by the player and upon such impact to yield with substantial cushioning effect and thereafter to react against the bowl and impel it upon a relatively short return or recoil movement at a retarded rate, the cushion having an active flat front face against which the bowl impinges when thrown, such front face extending upwardly from the floor to an elevation substantially greater than the vertical diametric plane of the bowl as thrown, the front face being inclined to extend in overhanging relation to the floor, the angle of inclination being such as to prevent bouncing of the bowl on its return movement as effected by the cushion, and a floor engaging frame by which the cushion is supported and within which it is secured, the frame exposing the active front face of the cushion to the bowl as thrown by the player.

2. A portable game apparatus as set forth in claim 1 wherein the cushion has a vertical rear face and vertical side faces and the frame comprises a rear bar which adjoins the rear face of the cushion, side bars connected to the ends of the rear bar and projecting forward in adjoining relation to the side faces of the cushion, the side bars projecting to some extent beyond the active face of the cushion and securing members attached to the inner faces of the projecting portions of the side bars and having inclined cushion engaging faces which uniformly bear with some degree of clamping pressure upon the ends of the active front face of the cushion.

3. A portable game apparatus as set forth in claim 1 wherein the side bars of the frame project beyond the active front face of the cushion and wings are connected to the projecting portions of the side bars and extend in diverging relation, the wings serving to intercept any wild throws of the bowl.

4. A portable game apparatus as set forth in claim 2 wherein the securing members have edge faces which terminate short of the edge faces of the side bars and provide rabbets, the rabbet at one side of the frame being of greater depth than the rabbet at the other side, and wherein wings are hingedly connected to the projecting portions of the side bars and by virtue of the rabbets may be folded in parallel relation to one another and to the cushion when the use of the apparatus is not required.

5. A portable game apparatus as set forth in claim 1 wherein the cushion is composed of foam rubber.
